UNITED STATES PATENT OFFICE.

CHARLES TORRÈS WEYMANN, OF PARIS, FRANCE.

LIQUID ELEVATOR.

Application filed February 1, 1922, Serial No. 533,460, and in France February 2, 1921.

It is known that liquid elevators operating by pressure and vacuum of gas and particularly those used for feeding heat engines with hydrocarbon, generally comprise for the admission and exhaust of the motive gas, valves controlled at the proper time by the displacement of a float which follows the variations of level of the liquid within the body of the apparatus.

10 In these latter apparatus, one of the valves is adapted to place in relation with a source of vacuum the inner capacity of the apparatus, so as to permit a flow of liquid thereto, and the other valve is adapted to put this capacity in communication with the atmosphere, in order to permit the free flow of the liquid by gravity towards its point of utilization.

20 The hydrostatic thrust of the float being directly used for actuating these valves, must be sufficient for overcoming the difference of pressures acting on either side of the latter.

It is thus necessary to use in practice floats of considerable size, necessitating an elevating apparatus having an excessive volume out of proportion with the useful volume of hydrocarbon which it admits and evacuates at each pulse.

30 This invention has for its object improvements in the said apparatus, these improvements being mainly adapted to reduce the volume which had to be given, up to now, to the float and to determine at the required moments of the cycle the action of relatively large valves even if they are subjected to high differences of pressures, by means of the movements of a very small float.

For that purpose, the movements of the said floats are utilized only for putting in action an auxiliary mechanism fed by any source of energy whatever and particularly by the main driving pressure or source of vacuum, this mechanism being consequently capable of controlling the valves of the apparatus with a power as high as desired.

40 This arrangement not only permits the use of very small floats, but it ensures also the possibility of providing a new category of elevators operating with cycles different from those previously used.

45 In the accompanying diagrammatic drawing and by way of example:

50 Figs. 1 and 2 illustrate two elevators made in accordance with the characteristic features of the present invention.

Fig. 1 shows a form of construction of a vacuum controlled elevator, in which the control, by the float, of a single small valve, produces, through the medium of an auxiliary piston, the operation of a large valve 60 opening to the atmosphere, which suffices to determine the alternate periods of pressure and vacuum necessary for the working of the apparatus.

65 *a* designates the body of the elevator adapted to raise the liquid from the reservoir *b* to the vessel of utilization *c* arranged at a higher lever than *b*.

This elevator *a* is connected by a piping *d* with the reservoir *b* and is provided at its lower part with a valve *e* through which the liquid periodically sucked by the said elevator *a* can, in the interval of the suctions, flow by gravity towards the reservoir *c*.

70 The elevator is, on the other hand, capable of communicating with the atmosphere through a large valve *f* alternately controlled, through the lever *g*, by the piston *h* and the return spring *i* of an auxiliary cylinder *j* 75 opening in the elevator *a*. The head of this auxiliary cylinder is in constant communication with the source of vacuum through a piping *j'* provided with an adjusting diaphragm *k*. This cylinder is in intermittent communication with the elevator *a* through a piping *l*, the orifice of which is capable of being closed at the required times by a needle valve *n* which is connected, by the lever *o*, 80 to the float *p*.

85 The operation of such an apparatus is as follows:

When the float *p* is in its lowermost position, the needle valve *n* is open and the vacuum is also left in the auxiliary cylinder *j* and in the body of the elevator *a*. The piston *h* being thus subjected to equal pressures on both its faces, yields to the return spring *i* without resistance and maintains the atmospheric valve *f* in its closed position.

90 The vacuum increases rapidly within the elevator *a* and permits the flow thereto of the liquid sucked through the piping *d*. This flow of liquid tends to diminish the vacuum existing behind the diaphragm *k* in the elevator *a* and in the auxiliary cylinder; this 95 vacuum depends at the same time, on the difference of level of the reservoirs *a* and *b*, on the resistance of the pipe *d* to the flow of the liquid, and on the relative braking of the air sucked through the diaphragm and the 100 105 110

piping l , etc., but keeps in the main a value d' sensibly the same as d (source of vacuum).

When the level of the liquid sucked in the elevator a becomes sufficient for lifting the 5 float p , the latter rises drawing along with it the needle valve n which cuts off the communication of the elevator a with the cylinder j and the source of vacuum.

From this fact, the vacuum d existing in 10 the said elevator, will progressively diminish, considering the persistent flow of the liquid and will take a value d^2 sensibly less than d^1 and which, at the limit, has only for its 15 value the difference in the levels of the liquid in the reservoirs a and b . Simultaneously the vacuum d^1 existing in the cylinder j will increase again up to the value d , the leakage through the needle valve n which 20 was weakening it being stopped.
25 The piston p on which is then exerted this notable difference of pressure ($d-d^2$) is therefore at this moment energetically sucked upwardly and raises the large valve f which had previously been pressed upon its seat by the vacuum d^1 d^2 and spring i .

Through this large orifice, atmospheric 30 air enters freely in the elevator and allows the liquid it contains to flow by gravity into the reservoir c by pushing back the exhaust valve e . During this exit, the float p progressively emerges from the liquid and its 35 Archimedean thrust, diminishing its weight, finally overcoming the resistance of the needle valve n pressed upon its seat by the depression d suddenly opening the orifice of the piping l .

The atmospheric pressure existing in the elevator a , then enters freely, through this piping, into the cylinder j where it efficiently 40 offsets the effect of the vacuum entering only through the small diaphragmed orifice k .

The vacuum existing in the cylinder j becomes therefore very small and is insufficient 45 for permitting the piston to resist to the return spring i . The latter therefore pushes back the piston and determines the closing of the atmospheric valve f which is before long effectively pressed upon its seat by vacuum again produced in the elevator.

50 Simultaneously the liquid ceases to flow; the exhaust valve e closes, the apparatus comes back to its starting position, and the above described cycle begins over again.

It will be noted in this apparatus:

55 1. that the difference of vacuum $d-d^2$, ensuring the movement of the piston, can be extremely small and permit however the opening of a very large atmospheric valve, provided the piston h has a suitable cross section.

60 2. that considering the form of the cycle described, the use of a very large air valve allows to obtain by the simple operation of the latter the succession of the pressures and 65 vacuum determining the suction and the flow

of the liquid, without necessitating simultaneously the control of the admission and cutting off of vacuum.

3. that, moreover, the use of the control needle valve n of the auxiliary mechanism 70 as orifice of introduction of the vacuum in the elevator cuts off precisely at the suitable times the communication between the elevator and the source of vacuum in the best conditions and without necessitating the use of 75 a special member for that purpose.

By way of example, Fig. 2 shows an apparatus comprising the same parts and in which the elevator is in constant communication with the source of vacuum, the auxiliary cylinder being intermittently connected thereto. 80

What I claim as my invention and desire to secure by Letters Patent is:

1. In a liquid elevator operating by the pressure variation of an elastic fluid, a chamber having an opening communicating with the atmosphere, a valve of large diameter controlling the opening, a lever bearing on said elevator and carrying said valve, a servomotor including a piston, a cylinder for said piston mounted on the chamber of the elevator and communicating therewith, the lever being connected with the piston of the servomotor, a spring acting on said piston to hold the valve applied on its seat and means to pneumatically actuate the piston of the servomotor and the co-operating air valve. 95

2. In a liquid elevator operating by the pressure variation of an elastic fluid, a chamber having an opening communicating with the atmosphere, a valve of large diameter controlling the opening, a lever bearing on said elevator and carrying said valve, a servomotor including a piston, a cylinder for said piston mounted on the chamber of the elevator and communicating therewith, the lever being connected with the piston of the servomotor, a spring acting on said piston to hold the valve applied on its seat and means to pneumatically actuate the piston of the servomotor and the co-operating air valve, a small float inside the elevator chamber to produce the variations of pressure of the elastic fluid to actuate the servomotor piston pneumatically. 110

3. In a liquid elevator operating by the pressure variation of an elastic fluid, a chamber having an opening communicating with the atmosphere, a valve of large diameter controlling the opening, a lever bearing on said elevator and carrying said valve, a servomotor including a piston, a cylinder for said piston mounted on the chamber of the elevator and communicating therewith, the lever being connected with the piston of the servomotor, a spring acting on said piston to hold the valve applied on its seat and means to pneumatically actuate the piston of the servomotor and the co-operating air valve, a small float inside the elevator chamber subject to 125

the variations of the level of the liquid in said latter, a lever pivoted on the elevator and carrying said float and a valve depending from said lever to produce the variations of pressure of the elastic fluid for actuating the servo-motor piston pneumatically.

4. In a liquid elevator operating by the pressure variation of an elastic fluid, a chamber having an opening communicating with the atmosphere, a valve of large diameter controlling the opening, a lever bearing on said elevator and carrying said valve, a servo-motor including a piston, a cylinder for said piston mounted on the chamber of the elevator and communicating therewith, the lever being connected with the piston of the servo-

motor, a spring acting on said piston to hold the valve applied on its seat and means to pneumatically actuate the piston of the servo-motor and the co-operating air valve, a small float inside the elevator chamber subject to the variations of the level of the liquid in said latter, a lever pivoted on the elevator and carrying said float and a valve depending from said lever to control the cross section of the opening which permits the vacuum to act pneumatically on the piston of the servo-motor.

In testimony whereof I have affixed my signature.

CHARLES TORRÈS WEYMANN.
